United States Patent Office

Des. 193,037
Patented June 12, 1962

193,037

CATCHUP DISPENSER

William H. Harnage, Huntington Park, Calif., assignor to
The Drackett Company, Cincinnati, Ohio, a corporation of Ohio

Filed May 19, 1961, Ser. No. 65,241

Term of patent 14 years

(Cl. D62—2)

FIGURE 2 is a side elevation thereof; and
I claim:
The ornamental design for a catchup dispenser, substantially as shown.
